Primary Examiner — Melody N Brown(74) *Attorney, Agent, or Firm* — Reising Ethington P.C.(57) **CLAIM**

The ornamental design for a vehicle rear bumper, as shown and described.

DESCRIPTION

FIG. 1 is a front perspective view of a vehicle rear bumper showing my new design;

FIG. 2 is a front elevational view thereof;

FIG. 3 is a left side perspective view thereof, the right side being substantially a mirror image thereof; and,

FIG. 4 is a top plan view thereof.

The broken lines shown in the drawings depict portions of the vehicle rear bumper that form no part of the claimed design.
